UNITED STATES PATENT OFFICE.

JOHN R. GILDA, OF ST. LOUIS, MISSOURI, ASSIGNOR OF ONE-HALF TO WM. SCHIELD,
OF ST. LOUIS, MISSOURI.

LYE-CRUSHING MACHINE.

1,375,503.

Specification of Letters Patent. Patented Apr. 19, 1921.

Application filed November 1, 1918. Serial No. 260,652.

To all whom it may concern:

Be it known that I, JOHN R. GILDA, a citizen of the United States, residing at the city of St. Louis, State of Missouri, have 5 invented certain new and useful Improvements in Lye-Crushing Machines, of which the following is a specification, reference being had to the accompanying drawings, forming a part thereof.

10 This invention relates generally to reducing or crushing machines and, more particularly, to certain new and useful improvements in machines especially adapted for crushing lye, the chief object of my present 15 invention being to provide a readily operated machine, simple, positive, and substantially automatic in its operations, for inexpensively, conveniently, and efficiently reducing, crushing, or breaking lye from a 20 hard, solid, one-piece or so-called "drum" form, into relatively small lumps or, as it might be described, into a more or less loosely divided form or condition, preparatory to 25 milling or grinding for commercial use in various compounds or preparations or for other desired purposes.

With the above and other objects in view, my invention resides in certain novel features of form, construction, arrangement, 30 and combination of parts, all as hereinafter described and afterward pointed out in the claims.

In the accompanying drawings,

Figure 1 is a side elevational view of a 35 machine constructed in accordance with and embodying my invention in preferred form;

Fig. 2 is a so-called rear end elevational view of the machine;

Fig. 3 is a plan view of the machine;

40 Fig. 4 is a detail elevational view, partly in section, of the lye-drum advancing or feeding mechanism of the machine;

Fig. 5 is a detail sectional view of the releasing gears of the lye-drum feeding mechanism of the machine; and

50 Fig. 6 is an enlarged elevational view, partly broken away and in section, of the driving ratchet and its coöperating unidirectional pawls of the lye-drum feeding mechanism.

Referring to the said drawings, in which like reference characters refer to like parts throughout the several views, the frame of the machine comprises a pair of suitable

main standards 1—1, shown only fragmentarily and which are rigidly fixed together in parallel spaced relation by cross or tie-bars, not shown. Mounted upon the standards 1 and rigidly fixed thereto, as by tie-bolts 2, are substantially rectangular relatively heavy plates 3—3, disposed vertically in parallel correspondingly spaced relation, the plates 3 being preferably provided at and along their edges with outwardly presented flanges adapted not only to reinforce 65 the plates against buckling, but also for the convenient securement of various parts of the machine, as hereinafter more fully appears. Supported and suitably fixed at its side edges upon the top flanges of the plates 70 3 and extending across the machine therebetween, is a trough 4 preferably somewhat V-shaped in end or sectional elevation, as seen in Fig. 2, trough 4 constituting and providing a support or table for the lye-drum or other material to be worked or operated upon.

At the front end of the machine, the trough or table 4 has secured thereto a pair of cutting-blades 5, whose cutting edges substantially parallel the sectional trend of the trough, in order to provide a shearing cut, and thereby more efficiently coöperate, with a movable blade 6 disposed transversely of the trough 4 and substantially straight 85 throughout its length, the blades 5 being preferably detachable from the trough for purposes of sharpening, repair, and the like. The blade 6 is secured to and carried by a cross-head 7 arranged for reciprocatory vertical movement or travel in suitable guide or slide-ways formed or provided by parallel pairs of coöperating standards 8—9 disposed vertically at opposite sides of the machine, as seen in Figs. 1, 2, and 3, each pair 95 of said standards being preferably separably, for purposes of repair and the like, bolted together at their upper end and at their lower end to the front end flanges of the plates 3. The blade 6 is also, for similar purposes, preferably detachable from the cross-head 7, and the standards 9 are preferably reinforced by lengthwise extending webs 9'.

Mounted for rotation in suitably formed and positioned pairs of bearings in the plates 3, are shafts 10, 11, 12, and 13, which extend transversely of the machine beneath the

trough or table 4 and preferably project at each end beyond the outer face of the plates 3 for purposes shortly appearing.

Mounted on one projecting end of shaft 5 10 is a belt or other drive-wheel 14, and mounted on the other or opposite projecting end of the shaft 10 is a relatively small gear-wheel 15, which latter meshes with a somewhat larger gear-wheel 16 mounted upon 10 the corresponding end of shaft 12. Fixed on the shaft 12 intermediate the plates 3, is a relatively small gear-wheel 17, which meshes with a larger gear-wheel 18 correspondingly fixed on the shaft 13. Fixed on 15 one projecting end of the shaft 13, is a relatively small gear-wheel 19, which meshes with a relatively large gear-wheel 20 fixed upon the corresponding end of shaft 11, a wheel 21 having substantially the diameter 20 of wheel 20 being fixed upon the opposite end of shaft 11. Each wheel 20—21 carries a wrist-pin 22, which, in turn, are connected to the opposite ends of the cross-head 7 by operating pitmen 23, whereby the 25 cross-head 7 and its carried knife 6 are caused to reciprocatorily travel during the operation of the machine. The gears and their shafts described are compactly arranged in the machine and provide a simple 30 speed-reducing gear for the movable knife 6, the speed of reciprocation of the knife 6 being considerably less than the speed of rotation of the main or belt-wheel 14, and through the multiplication of reduction- 35 gears there is obtained in the machine relatively great power for the cross-head 7 and its carried knife 6 with a relatively small amount of power applied at the main or belt-wheel 14.

40 Fixed to the flanged rear end of the plates 3, is a pair of rearwardly presented brackets 24, mounted upon which in alining relation across the machine are small standards 25, each bracket 24 carrying two of 45 the standards 25 in properly spaced relation. Mounted for rotation in the standards 25 and extending transversely across the machine, are shafts 26—26, fixed upon which in tandem relation approximately centrally 50 of the machine are gear-wheels 27—27 arranged to mesh with a toothed rack 28 formed or provided longitudinally on a lengthwise movable push-bar 29 carrying at its forward end a suitable ram preferably in 55 the form of a circular plate 30 arranged to travel upon the trough or table 4 for feeding or advancing the lye-drum or other material being operated upon to the cutting-blades before described. Also mounted for rotation 60 in the standards 25 and extending transversely of the machine above the shafts 26, are shafts 31—31, which carry grooved idlers 32 immediately above the gears 27—27, adapted to engage the push-bar 29 to hold 65 the same in operative position in the ma-

chine and also in engagement with the gears 27—27.

Mounted upon the brackets 24 intermediate the standards 25, in an alining pair of standards 33, and mounted for rotation in 70 the standards 33 and also extending transversely of the machine, is a shaft 34 having loosely mounted for rotation thereupon a gear-wheel 35 meshing with the push-bar rack 28 for feeding the push-bar 29 and its 75 carried ram 30 forwardly. Keyed or otherwise fixed to the shaft 34 to one side of the gear-wheel 35, is a peripherally grooved wheel 36, having mounted thereupon a preferably adjustable friction-band 37, suitably 80 engaging with which are pins 38 projecting laterally from the gear-wheel 35. Such construction forms a clutch or friction drive for the ram-feeding or driving gear-wheel 35 and provides for "slipping" to prevent 85 breakage of the feeding mechanism in the event of a jam in the material.

Keyed or otherwise fixed to the shaft 34 to the opposite side of the gear-wheel 35, is a shaft-driving ratchet-wheel 39, and mounted to oscillate upon the shaft 34 to one side of the ratchet-wheel 39, is a lever comprising arms 40—41, the lever-arm 40 having or being provided at its free end with a socket 42 and spaced perforated ears 43—43. 90 Mounted for rotatory movement in the ears 43—43, is a rock-shaft 44 which carries a pawl 45 adapted for coöperative driving engagement with the ratchet-wheel 39 and a releasing arm 46 adapted for engagement 95 by a pin 47 carried by the gear-wheel 35. The ratchet-operating pawl 45 is spring-held to its working or driving position by means comprising a non-circular block 48 fixed on the shaft 44 and a coöperating spring-pressed disk 49 disposed in the lever-socket 42 immediately therebeneath. Normally, under the spring-pressure of its coöperating disk 49, the block 48 is in the position thereof shown in full lines in Fig. 6, and when 100 in such position, the pawl 45 will be yieldingly held in driving engagement with the ratchet-wheel 39. Opposite lever-arm 41 is pivotally connected at its free end to one end of a forwardly projecting link 50 pivotally connected at its other end to one end of a lever 51 suitably mounted for oscillatory movement upon a transverse shaft 53 supported at its ends by the plates 3. Pivotally connected at one end to the lever 51 at 110 a point intermediate the shaft 53 and the pivoted connection between lever 51 and link 50, is a link or bar 54 provided at its other end with an elongated eye 55 embracing the shaft 11, the shaft 11 thus providing a support for the free end of the link or bar 54. Mounted on the shaft 11 adjacent the bar 54, 115 is a cam 56 arranged to engage a roller 57 mounted on the link 54 and thereby, on each rotation of the shaft 11, actuate the bar 54 120 125 130

rearwardly against the tension of a restoring-spring 58 fastened at its opposite ends to one of the frame-standards 1 and to the lower or free end of the oscillating lever 51. Thus, as will be evident, as the shaft 11 is rotated, the pawl 45, through its supporting oscillatory lever and its said lever's link and lever connection with the shaft 11, will be caused to successively engage the teeth 10 of, and thereby, drive the ratchet-wheel 39 and, following, through the shaft 34, clutch-wheel 36, and gear-wheel 35, effect a step-by-step progression of the ram 30 and consequent forward feeding of the material being 15 acted upon toward the coöperating cutting-blades at the front end of the machine, the movable blade 6 being reciprocated vertically on each rotation of the shaft 11. The parts of my machine are so relatively proportioned that, on each complete revolution 20 of the ram driving gear 35, the ram 30 will be actuated forwardly a distance approximately equal to the length of the table or trough 4, the forward progressive movement 25 of the ram 30 continuing until on the rotation of gear 35, its carried pin 47 is brought into engagement with the shaft-arm 46. On engagement of the arm 46 by the pin 47, the shaft 44 will be rocked sufficiently to lift the pawl 45 from operative 30 engagement with the ratchet-wheel 39, the pawl 45 thereafter, and until again brought into driving engagement with the ratchet-wheel 39, oscillating without effect upon the 35 ratchet-wheel 39. At the same time, on the described rocking of the shaft 44, the block 48 will be caused to present a flat face, as at 48", to the disk 49, or, in other words, caused to occupy the position thereof shown in 40 dotted lines in Fig. 6, and pawl 45, through its supporting-shaft 44, yieldingly held in elevated position out of engagement with the ratchet-wheel 39.

The reduction or crushing of a lye-drum 45 or other material being operated upon having been accomplished by the coöperating blades during such forward progressive movement of the ram 30, and the pawl 45 being now out of driving engagement with 50 the ratchet-wheel 39, the ram 30 is returned to its original, rearmost or starting position, and for such purpose a suitable sprocket-wheel 59 is fixed upon one end of one, and preferably the rear, shaft 26, which, as before 55 described, carries a gear-wheel 27 meshing with the rack 28 of the ram. This sprocket-wheel 59 is chain or otherwise suitably connected with a second sprocket-wheel 60 suitably mounted upon the frame of the machine and provided with an operating crank 61 conveniently accessible to an operator on the ground. Or, for a similar purpose, the said shaft 26 may be provided with a hand-wheel 62 for convenient rotation by an 65 operator on the machine. The ram 30 being

so returned to starting position, a push-rod 63 having connection at its upper end with an arm 64 rigidly connected to the shaft 44 is manually lifted by the operator and shaft 44 reversely rocked to restore the block 48, 70 against the tension of its spring-pressed co-operating disk 49, to its described normal position, the pawl 45 being accordingly returned to driving engagement with the ratchet-wheel 39. 75

To hold the ram 30 from retrograde movement during cutting operations of the blades, I provide a holding or unidirectional pawl 65 for gravity engagement with the ratchet-wheel 39, the pawl 65 being suitably mounted loosely upon preferably the rear shaft 26, as seen particularly in Fig. 3. When the main or driving pawl 45 is lifted or moved out of operative driving engagement with the ratchet-wheel 39, the holding pawl 65 will be likewise moved, as indicated by dotted lines in Fig. 6, by means of a lifter 66, which is fixed at one end to the holding-pawl 65 and which, at its other end, loosely rests on the driving-pawl 45, as shown. 80 85 90

I am aware that changes in the form, construction, arrangement, and combination of the several parts of my machine may be made and substituted for those herein shown and described without departing from the 95 nature and principle of my invention.

Having thus described my invention, what I claim and desire to secure by Letters Patent is:

1. A material crushing machine comprising, in combination, a table, a reciprocatory cutting-blade, a ram for feeding material along the table to the blade, and mechanism for synchronously reciprocating the blade and effecting a progressive step-by-step movement of the ram, said mechanism including a rack-bar fixed to the ram, a driving gear meshing with the rack-bar, a pawl and ratchet having driving connection with the gear, pitmen pivotally connected to the 100 cutting-blade, a rotary shaft, and operating connections between the shaft and both the pawl and pitmen. 105 110

2. A material crushing machine comprising, in combination, a table, a reciprocatory cutting-blade, means for feeding material along the table to the blade, and mechanism for reciprocating the blade and effecting a progressive step-by-step movement of the feeding means, said mechanism including a 115 rack-bar fixed to the ram, a driving gear meshing with the rack-bar, a pawl and ratchet having driving connection with the gear, a rotary shaft, disks on the shaft, a cam on the shaft, pitmen pivotally connected to the 120 disks and to the blade, and link and lever operating connections between the pawl and shaft adapted for actuation by the cam on rotation of the shaft. 125

3. A material crushing machine comprising, 130

ing a table and a reciprocatory cutting-blade, in combination with a ram for feeding material along the table to the blade, mechanism including a pair of coöperating 5 interengaging members for effecting a progressive feeding movement of the ram, and means for automatically disengaging said members to effect a stoppage of the feeding movement of the ram after a predetermined

10 travel.

4. A material crushing machine comprising, in combination with a table and a reciprocatory cutting-blade, a ram for feeding material along the table to the blade, 15 and mechanism for effecting a progressive step-by-step feeding movement of the ram, said mechanism including a rack carried by the ram, a driving gear meshing with the rack, a ratchet-wheel for driving the gear, 20 a pawl for driving the ratchet-wheel, a rotary shaft, a cam on the shaft, and link and lever operating connections between the pawl and shaft adapted for actuation by the cam on rotation of the shaft.

5. A material crushing machine comprising, in combination with a table and a reciprocatory cutting-blade, a ram for feeding material along the table to the blade, mechanism including a coöperating ratchet- 30 wheel and driving-pawl for effecting a progressive feeding movement of the ram, and means for automatically tripping the pawl out of driving engagement with the ratchet-wheel to effect a stoppage of feeding movement of the ram after a predetermined 35 travel.

6. A material crushing machine comprising, in combination with a table and a reciprocatory cutting-blade, a ram for feeding 40 material along the table to the blade, mechanism for effecting a progressive feeding movement of the ram, said mechanism including a yieldingly held rock-shaft, a ratchet-wheel, and a pawl on the shaft normally in driving engagement with the ratchet-wheel, and means for automatically 45 rocking the shaft to lift the pawl out of driving engagement with the ratchet-wheel to effect a stoppage of feeding movement 50 of the ram after a predetermined travel.

7. A material crushing machine comprising, in combination with a table and a reciprocatory cutting-blade, a ram for feeding material along the table to the blade, mechanism for effecting a progressive feeding movement of the ram, said mechanism including a rotary shaft, a yieldingly held rock-shaft, a gear-wheel on the rotary shaft, 55 a ratchet-wheel on the rotary shaft, and a pawl on the rock-shaft normally in driving engagement with the ratchet-wheel, and means including coöperating members on the gear-wheel and rock-shaft for automatically 60 rocking the rock-shaft to lift the pawl out of driving engagement with the ratchet-

wheel to effect a stoppage of feeding movement of the ram after a predetermined travel.

8. A material crushing machine comprising, in combination with a table and a reciprocatory cutting-blade, a ram for feeding material along the table to the blade, mechanism including a ratchet-wheel and a coöperating pawl for effecting a progressive feeding movement of the ram, means 70 for lifting the pawl out of driving engagement with the ratchet-wheel to effect a stoppage of feeding movement of the ram, and means for restoring the pawl into driving engagement with the ratchet-wheel. 75

9. A material crushing machine comprising, in combination with a table and a reciprocatory cutting-blade, a ram for feeding material along the table to the blade, means including a ratchet-wheel for effecting a 80 feeding movement of the ram, a yieldingly held rock-shaft, a pawl on the rock-shaft for actuating the ratchet-wheel, the pawl being normally in driving engagement with the ratchet-wheel, means for rocking the shaft to lift the ratchet-wheel out of normal 85 driving engagement with the ratchet-wheel to effect a stoppage of feeding movement of the ram, and means for reversely rocking the shaft to restore the pawl into normal 90 driving engagement with the ratchet-wheel. 95

10. A material crushing machine comprising, in combination with a table and a reciprocatory cutting-blade, a ram for feeding material along the table to the blade, 100 and a slip-providing drive mechanism for the ram.

11. A material crushing machine comprising, in combination with a table and a reciprocatory cutting-blade, a ram for feeding 105 material along the table to the blade, and a slip-providing drive mechanism for the ram, said mechanism including a rotary shaft, a friction-wheel fixed to the shaft, a gear-wheel loosely mounted on the shaft, a 110 friction-band upon the friction-wheel, and lateral pins on the gear-wheel having engagement with said band.

12. A material crushing machine comprising, in combination, a table, guide-way providing standards disposed approximately 115 vertically relatively to the table, a cutting-blade carrying cross-head mounted for reciprocatory movement in said guide-ways at an angle relatively to the table, mechanism for feeding material along the table to the cross-head, and mechanism for reciprocating the cross-head and its carried blade, said last named mechanism including a rotary shaft, wheels fixed to the shaft, 120 and pitmen pivotally connected to said wheels and to the cross-head. 125

In testimony whereof, I have signed my name to this specification.

JOHN R. GILDA.
